UNITED STATES PATENT OFFICE.

MARGARET CATHERINE BAATZ, OF IRVINGTON, NEW JERSEY, ASSIGNOR TO CHAS. R. DE BEVOISE COMPANY, OF NEWARK, NEW JERSEY, A CORPORATION OF NEW JERSEY.

BRASSIÈRE.

Application filed March 16, 1923, Serial No. 625,608. Renewed December 20, 1926.

This invention relates to brassières and proposes the construction of an article of apparel of this class in which provision is made for supporting the bust in a substantial and comfortable manner at the same time affording a positive resisting and reducing means for that part of the figure at the diaphragm.

One of the objects of the invention is to construct a brassière having an unstiffened body portion surrounding the bust and a relatively stiff diaphragm section.

Another object of the invention is to provide a body portion surrounding the bust for the support of the same and securable thereabout, and a diaphragm section unitarily related to said body portion and independently securable about the figure of the wearer.

Still another object of the invention is to provide the body portion with a diaphragm section secured thereto or integral therewith and constructed to exert elastic pressure upon the diaphragm when the brassière is secured in position, said diaphragm section being provided with additional means for pressing it against the figure of the wearer.

A further object of the invention is the construction of the brassière in which the body portion extends over the diaphragm section both to conceal the latter and to reinforce it.

With the above and other objects in view, my invention consists in the improved brassière illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:—

Figure 1 is an elevational view of the brassière extended.

Figure 2 is a side elevation of the brassière as worn.

Figure 3 is a cross section taken along the line 3—3 of Figure 2.

Figure 4 is an elevational view of another form of the invention.

Figure 5 is a side elevation of the modification shown in Figure 4 applied to a person.

Figure 6 is a cross section taken along the line 6—6 of Figure 5.

Referring now in detail to the several figures, the brassière consists of a body portion 1 divided at the back and adapted to surround the body of the wearer at the bust, being securable thereabout by means of the series of hooks and eyes 2 or other suitable fastening means arranged along the free edges 3 and 4 of the body portion. The latter is suspended by means of the shoulder straps 5 and is so shaped as to support the bust in a substantial and comfortable manner.

The particular construction of the body portion 1 is not material to the present invention although it is shown as being formed in its lower part with elastic gores or inserts 6 which cooperate in a novel and patentable manner with the diaphragm reducing section 7 now to be described.

Said diaphragm reducing section comprises a piece of material 8 which is preferably stiffened by means of bones or other stiffening devices 9 which may be arranged either horizontally as shown in Figure 1 or vertically as illustrated in Figure 4 or in any other manner that may be deemed advantageous either in the improving of the article or in the manufacturing of the same.

The diaphragm reducing section 7 is wide at the middle, tapering toward the ends and is arranged unitarily with the body portion symmetrically with respect to the median line of the front thereof.

When the body portion is secured around the body of the wearer, the unstiffened material conforms to the contour of the bust permitting the latter to maintain its natural shape, while the stiffened portion comprising the dia-

phragm section remains relatively flat, exerting a pressure against the body in the region of the diaphragm, supporting and reducing the figure of the wearer at the point of pressure.

The pressure thus applied is resilient or yielding in its nature due to the elastic gores or inserts 6 which are arranged in the body portion intermediate the hooks and eyes 2 and the dia-

phragm supporting section. The pressure of the diaphragm section may be controlled

independently of the body portion by means of the elastic straps 10 and 11 which are secured within the brassière to the sides of said diaphragm reducing section and adapted to extend around the body being secured together at the back by means of the hook-and-eye 12 or other suitable fastening means. In this form of the invention the material of the body portion covers the diaphragm reducing section and extends below it, the tape 13 and the hook 14 being secured to the lower edge of the body portion, said hook being adapted to engage with one of the fastening devices of the corset or with some other appropriate undergarment functioning both to prevent the brassière riding above the upper edge of the corset and to further preserve the flat shape of the diaphragm reducing portion. The body portion not only serves to hold the diaphragm reducing section flat, but it reinforces said diaphragm reducing section and conceals it rendering it entirely invisible when the brassière is worn beneath outer garments of thin texture.

In the modification of the invention shown in Figure 4 the diaphragm reducing section is inserted in the body portion as a part thereof, instead of being applied thereto as in the first modification. This difference in construction results in the diaphragm reducing portion bearing the entire strain imposed by the tension of the elastic inserts 15 instead of said strain being carried primarily by the material of the body portion as is the case in the form of the invention shown in Figure 1. By this means a given tension of the brassière about the waist of the wearer is able to produce a more flattening effect upon the diaphragm reducing portion in the modification shown in Figure 4 than is possible in the other modification.

It is obvious that various changes may be made in the details of construction without departing from the invention and it is therefore to be understood that this inven-

tion is not to be limited to the specific construction shown and described.

Having described my invention what I claim as new and desire to secure by Letters Patent, is:—

1. A brassière comprising a bust supporting portion having the lower part thereof provided with inserts elongatable circumferentially of the brassière, a diaphragm reducing section underlying and secured to the front of the bust supporting portion and having circumferentially elongatable portions lying in the zone of said inserts and securable about the body for tensioning said diaphragm reducing section, and independent means for fastening said bust supporting portion about the body thereby imparting additional tension to said diaphragm reducing section.

2. A brassière comprising a diaphragm reducing section and a bust supporting portion overlying said diaphragm reducing section increasing the stiffness of the brassière in the area of said diaphragm reducing section, and to the front of which said diaphragm reducing section is secured, said bust supporting portion being provided with elastic inserts in the zone of said diaphragm reducing section, fastening means for securing said bust supporting portion around the body thereby tensioning said diaphragm reducing section in a circumferential direction, said diaphragm reducing section being provided with independent means securable about the body for imparting additional lateral tension to said diaphragm reducing section and independent tensioning means carried by said bust supporting portion for imparting tension to both said bust supporting portion and diaphragm reducing section in a direction transverse to the line of pressure imparted by both of said other tensioning means.

In testimony whereof I have hereunto set my hand.

MARGARET CATHERINE BAATZ.
